UNITED STATES PATENT OFFICE.

EDWIN L. RELLER AND VICTOR R. A. STROH, OF ST. LOUIS, MISSOURI, ASSIGNEES TO THE WATTERS CORPORATION, OF WILMINGTON, DELAWARE, A CORPORATION OF DELAWARE.

ACCOUNT-FINDING MACHINE.

Application filed November 8, 1920. Serial No. 422,660.

This invention relates to driving mechanisms and means for starting, stopping and controlling the same. The mechanism illustrated applies more particularly to driving means such as used in connection with the account finding machine described in copending application Serial Number 352,601, filed January 19, 1920.

As such machines are often motor driven so as to save the time and effort of the operator, it is desirable to provide for automatically stopping the motor when the operator leaves the machine for an extended period, in order to avoid a waste of electric power by allowing the motor to run when there is no need of its service. Such means should be entirely automatic in order to guard against forgetfulness or negligence on the part of the operator.

One of the objects of this invention is to provide means for driving such a machine in which the source of driving power will be automatically stopped at the end of a predetermined time interval in case the operator should fail to stop it.

Another object of this invention is to provide such driving means in which the driving source of power is maintained continuously available so long as the device is in use, but in which said source will be rendered inoperative upon the lapse of a predetermined time interval after such use has ceased.

Further objects will appear from the following description taken in connection with the accompanying drawings in which:

Figure 1 is a plan view of the controlling device;

Figure 2 is a view partly in section taken on line 2-2 of Figure 5 and showing the time switch;

Figure 3 is an end view of the controlling mechanism taken on line 3-3 of Figure 5 and of which Figure 1 is a top view;

Figure 4 is a detail sectional view taken on line 4-4 of Figure 5;

Figure 5 is a sectional view of the driving and controlling mechanism;

Figure 6 is a view partly in section showing the relation of the driving and controlling mechanism to the driven device; and

Figure 7 is an outline view of the driven device showing the arrangement of the manipulative elements.

Referring now to the accompanying drawings, 1 designates a constant-speed electric motor or a similar driving element connected to the main drive shaft 2. The shaft 2 carries a worm 3 meshing with a worm wheel 4. The worm wheel 4 is mounted upon a sleeve 5 having a bearing in the housing 6, and having a running fit over the short shaft 7 which in turn has a bearing in the end plate 8. The worm wheel 4 is keyed to the sleeve 5 by means of the small pins 9.

The worm wheel 4 is bored out to provide a chamber 10 in which a cam member 11 is adapted to rotate, said member being fixed to the shaft 7 by means of a pin in a well known manner. The member 11 has cam faces 12 symmetrically disposed and adapted for cooperation with a set of rollers or dogs 13 and the inner cylindrical face of the chamber 10, to lock the shaft 7 and the worm wheel 4 together when the driving effort is in one direction of rotation, and to release them when said effort is in the opposite direction. Mounted on opposite sides of the cam member are two plates 14 and 15 connected together by means of studs or rivets 16 passing through circumferential slots 17 in the member 11. These plates are adapted to rotate about the hub of the member 11 within the limits allowed by the slots 17. The dogs or rollers 13 have reduced end portions adapted to work in radial slots 18 in the plates 14 and 15. A spring 19 is attached at one end to the plate 15 and at the other end to a pin 20 passing through a circumferential slot in the plate 15 and fixed to the cam member 11. The function of the spring 19 is to move the cam member 11 and the connected plates 14 and 15, and thereby the rollers 13, in such a direction with respect to one another as to cause said rollers to engage between the cam surface 12 and the interior face of the chamber 10 so as to lock the shaft 7 to the worm wheel 4.

The outer edge of the plate 14 has a spiral shape, adapted to form a notch or tooth 21 adapted to engage a stop member 22 connected with the manipulative mechanism, when said stop member is positioned in the path of said tooth. As the driving effort is in such a direction as to cause rotation in the direction indicated by the arrow in

Figure 6, it will be seen that when the stop member 22 is positioned to engage the tooth 21, the plate 14 will be arrested thereby, with the result that the rollers 13 will be 5 moved so as to disengage the clutch member 11 from the worm wheel 4 thereby arresting the rotation of the shaft 7. The shaft 7 is connected to operate the accounting device through the crank 23 and the link 24.

19 It will be seen that when the stop 22 is moved out of engagement with the tooth 21, the spring 19 will move the plates 14 and 15 so as to carry the dogs 13 into engagement with the cam faces 12 and the inner rim of 13 the worm wheel 4, thereby connecting the shaft 7 so as to be driven by the shaft 2 to operate the accounting device. It will also be seen that when the stop member 22 engages the dog 21 the motion of the shaft 20 7 will be arrested.

The stop member 22 is connected to a lever 25 pivoted at 26 the other end of which is connected by means of a link 27 to an arm 28 on a rock shaft 29. The shaft 29 carries 25 a pair of arms 30 the outer ends of which engage pins 31 on a pair of bell cranks 32 pivoted at 33, the other arms of said bell cranks engaging pins 34 on the side bars 35 of a manipulative key 36. It will be 30 seen that by pressing down on the key 36, the bell crank 32 will be rocked to move the arm 30 to the left, Figure 6, thereby rotating the rock shaft 29 so as to move the arm 28 downwardly and, through the link 35 27, to actuate the lever 25 so as to lift the stop member 22 out of engagement with the tooth 21 thereby starting the mechanism. These parts being spring returned as shown, the member 22 will move into engagement 40 with the tooth 21 upon release of the key 36, but not until the shaft 7 has made one complete revolution.

Referring now to Figures 1 to 5 inclusive, the sleeve 5 has mounted on the end thereof, 45 the driving member 37 of an intermittent reduction gear comprising said driver and the follower 38. The follower 38 is mounted on a shaft 39 having bearings in the housing 40 and carrying near its other end, a worm 50 41 engaging a worm wheel 42 secured to a short shaft 43 having a bearing at one end in the end plate 44, and at the other in the housing 40. Fixed to the shaft 43 is a driving member 45 having cam faces 46 55 symmetrically disposed. On opposite sides of the driving member 45, are plates 47 and 48 loosely mounted on the shaft 43. Said plates are fastened together by means of studs 49 passing loosely through circumferential slots 50 in the member 45. The outer edge of the plate 47 is provided with ratchet teeth adapted to engage a dog 51 as hereinafter described.

A spring 52 is fastened at one end to 65 the plate 47 and at the other to a pin 53

passing through a circumferential slot 54 in said plate and fixed to the driving member 45. Loosely mounted on the shaft 43 is a flanged member 55, the flange of which is adapted to surround the plate 48 and the driving member 45. Disposed between the inner face of the flange of the member 55 and the cam faces 46 on the driving member 45, is a pair of rollers or dogs 56. The dogs 56 are so placed that when the driving effort 75 of the member 45 is in the direction shown by the arrow in Figure 4, said dogs will be confined between the cam faces 46 of the flange of the member 55, thereby locking said flanged member to said driving member 80 so as to drive said flanged member 55. It will be seen that when the driving effort is in the opposite direction, said flanged member 55 will be released from said driving member 45. The rollers 56 are provided 85 with reduced ends adapted to work loosely in radial slots 57 in the plates 47 and 48 so that said rollers may be moved into and out of locking engagement by the movement of said plates relatively to the driving member 45. It will be seen that the spring 52 will normally move the plate 47 and its connected plate 48 relatively to the driving member 45 so that the rollers 56 will be moved into locking engagement with the 95 driving member 45 and the flanged member 55.

Loosely mounted on the shaft 43 and fixed to the flanged member 55 is a grooved collar 58 also mounted loosely on the shaft 43, and 100 fixed to the collar 58 is an insulating member 59 carrying on its outer edge a sectional metallic rim 60. Said rim 60 has a gap at one point in its circumference to accommodate a projection 61 on the insulating member 59. The projection 61 is machined flush with the outer cylindrical surface of the rim 60. The insulating member 59 carries a collar 62 also of insulating material having a projection 63 adapted to form a 110 stop as hereinafter described. The flanged member 55, the collar 58, the insulating member 59 and its collar 62 are all connected together and are adapted to turn together upon the shaft 43. The collar 58 has attached thereto a flexible strap 64 the other end of which is attached to the spring 65 anchored to the housing. The spring 65 acts through the strap 64 to turn the combination 55, 58 and 59 so as to bring the 120 stop 63 against a pin 66 on the housing 40.

The metallic member 60 is adapted to form a rotating switch contact and has bearing upon it a pair of brushes 67 of carbon or other suitable material adapted to collect electric current from the rim 60. Said brushes 67 are mounted upon rods 68, each mounted in a plug 69 and held in engagement with the contact 60 by means of a spring 70 as shown in Figure 5. With the 130

switch contact 60 in the position shown in Figure 2, electric current may be passed through the switch from one of the studs 68 to its brush 67, thence through the rim 5 60 to the other brush 67 and out to the second stud 68. If now the switch contact 60 is rotated in the direction shown by the arrow in Figure 2, the projection 61 will move round until it will eventually pass 10 under one of the brushes 67. At the moment when the brush 67 moves off of the metallic rim 60 so as to rest wholly upon the insulating projection 61, the electrical circuit from one stud 68 to the other will be 15 broken.

The operation of the device is as follows: The circuit to the motor 1 is made to pass through the switch shown in Figure 2 by connecting to the studs 68. With the motor 20 running, the worm 3 will drive the worm wheel 4 continuously so long as the motor runs, thus rendering the source of power continuously available for driving the mechanism. Upon depressing the key 36, the 25 stop member 22 will, as described above, be moved out of engagement with the tooth 21. This will allow the shaft 7 to make one revolution to operate the mechanism through the arm 24, after which said plate 30 14 will be arrested by the engagement of the tooth 21 with the stop 22 thereby releasing the rollers 13 from locking engagement with the cam faces 12 and stopping the shaft 7. Thus each depression of the 35 key 36 will result in the operation of the mechanism through one cycle.

The rotating worm wheel 4, through the sleeve 5, the driving member 37, follower 38, shaft 39 and worm 41 will rotate the worm wheel 42, but at a very much reduced speed 40 on account of the high reduction ratio between the parts 37 and 38 and the worm gear 41 and 42. The worm gear 42 drives the shaft 43 and since the spring 52 maintains the rollers 56 in locking engagement, 45 the member 55 and the switch contact member 60 will rotate with the worm gear 42, the rotation of said switch contact 60 being in the direction shown by the arrow in Figure 2. It will be seen that if the rotation 50 of the contact 60 is not interrupted the insulating projection 61 will eventually come under one of the brushes 67, thereby opening the circuit of the motor 1, and stopping the entire apparatus. In practice, it is customary 55 to make the time interval required for the insulating plug 61 to travel from the position shown in Figure 2 around to circuit opening position about five minutes.

Attached to the rock shaft 29 is an arm 71 connected by means of a link 72 to one arm of a bell crank 73, pivoted at 74, the other arm of which is connected to a bar 75 which enters the switch housing 40 and carries at its inner end the dog 51, pivoted

on the arm 75 at 76 and held by a spring 77 against a stop 78. At each depression of the key 36, through the agency of the arms 30, and the rock shaft 29 acting as described above, the link 72 and the bell crank 73, the bar 75 will be pushed inwardly, or to the right as shown in Figures 1 and 4. Upon such movement the dog 51 will engage the ratchet teeth of the plate 47, thereby turning said plate in the direction 75 indicated by the arrow, in Figure 4, so as to move the dogs 56 out of locking engagement, thereby releasing the member 55 and allowing the spring 65 to turn the switch contact back until the stop 63 engages the 80 pin 66. It will be seen, therefore, that at every depression of the key 36, the driven mechanism will be operated through one cycle of operations and at the same time the time switch shown in Figure 2 will be 85 reset so as to extend the time interval during which the source of power is maintained available. It will also be seen that when the key 36 is not depressed for an extended 90 time interval as, for instance, when the operator leaves the machine, the time switch will operate after a predetermined time interval to render the driving means inoperative and stop the apparatus.

It is obvious that various changes may 95 be made in the details of construction without departing from the spirit of this invention; it is, therefore, to be understood, that this invention is not to be limited to the specific details shown and described. 100

Having thus described the invention what is claimed is:

1. In an electrically operated mechanism having a supply circuit, an automatic switch having a progressively moving contact, driving means, a clutch connecting said switch with said driving means to move said contact independently of said mechanism, means operating after a predetermined time interval to open said switch and stop said driving means, means for releasing said clutch, and means for closing said switch to start said driving means. 105

2. In an electrically operated mechanism having a supply circuit, an automatic switch 110 having a progressively moving contact, driving means, a clutch connecting said switch with said driving means to move said contact independently of said mechanism, means operating after a predetermined time interval to open said switch and stop said driving means, means operating upon manipulation of said mechanism for releasing said clutch, and means for closing said switch to start said driving means. 115

3. In an electrically operated mechanism having a supply circuit, an automatic switch 120 having a progressively moving contact, driving means, a clutch connecting said switch with said driving means to move said

contact independently of said mechanism, means operating after a predetermined time interval to open said switch and stop said driving means, means for releasing said clutch, and means adapted to reset said switch for timed operation.

4. An automatic time switch, comprising, a moving contact, driving means adapted to progressively move said contact, a clutch connecting said contact to said driving means, and means for releasing said clutch.

5. An automatic time switch, comprising, a moving contact, driving means adapted to progressively move said contact, a clutch having a driving member, a driven member and an intermediate locking member, adapted to connect said contact to said driving means, and means engaging said locking member adapted to release said clutch.

20 6. An automatic time switch, comprising, a moving contact, driving means adapted to progressively move said contact, a clutch connecting said contact to said driving means, means for releasing said clutch, and means for resetting said switch.

7. An automatic time switch, comprising, a moving contact, driving means adapted to progressively move said contact, a clutch connecting said contact to said driving means, means for releasing said clutch, and means operating upon release of said clutch to reset said switch.

8. In a power driven mechanism, driving means, a clutch connecting said means to the mechanism, means for releasing said clutch after a predetermined operation of the mechanism, an automatic time switch having a progressively moving contact independently connected to said driving means to move said contact and adapted for operation after a predetermined time interval to stop said driving means, and means adapted to simultaneously engage said clutch and reset said switch for timed operation.

45 9. In a power driven mechanism, driving means, a clutch connecting said means to the mechanism, means for releasing said clutch after a predetermined operation of the mech-

anism, an automatic switch having a progressively moving contact independently connected for operation by said driving means and adapted to stop said driving means after a predetermined time interval, and means adapted to simultaneously engage said clutch and reset said switch for timed operation.

10. In a power driven mechanism, driving means, a clutch connecting said means to the mechanism, means for releasing said clutch after a predetermined operation of the mechanism, an automatic switch having a progressively moving contact, means yieldingly opposing movement of said contact, a clutch adapted to connect said contact for operation by said driving means to stop said driving means after a predetermined time interval, and means adapted to simultaneously engage said first clutch and release said second clutch.

11. An automatic time switch, comprising, a moving contact, driving means adapted to move said contact through a series of closed-circuit positions to open-circuit position, a clutch connecting said contact to said driving means, and means for releasing said clutch.

12. An automatic time switch, comprising, a moving contact, driving means adapted to move said contact uniformly through a series of closed-circuit positions to open-circuit position, a clutch connecting said contact to said driving means, and means for releasing said clutch.

13. An automatic time switch, comprising, a moving contact, yielding means opposing the movement of said contact, driving means adapted to move said contact through a series of closed-circuit positions to open-circuit position, a clutch connecting said contact to said driving means, and means for releasing said clutch.

In testimony whereof we affix our signatures this 22nd day of September, 1920.

EDWIN L. RELLER.
VICTOR R. A. STROH.
